TYPEWRITING AND LIKE MACHINE

Russell E. Benner, Buffalo, N. Y., assignor to
 Remington Rand Inc., Buffalo, N. Y., a corpora-
 tion of Delaware

Application January 4, 1935, Serial No. 438

15 Claims. (Cl. 197—136)

My invention relates to typewriting and like machines and more particularly to card clamping means for cylindrical platens employed in such machines.

5 One of the main objects of my invention, generally stated, is to provide simple, comparatively inexpensive, and highly effective card clamping means.

A further object of my invention is to provide 10 improved means whereby a plurality of independently controlled card clamps may be employed on a single platen to enable a plurality of cards to be successively clamped in position along the platen without disturbing those already clamped in place, and in order to feed at one movement a plurality of cards arranged side by side on the platen and thereby materially increase the speed at which the cards may be written.

Another object of my invention is to provide 20 an improved card clamping means with which either a front or back feed of the cards may be effected without reversing the platen end-for-end or otherwise changing the construction.

A still further object of my invention is to so 25 construct and arrange the parts that the pressure for opening or releasing a clamp will be distributed equally throughout the length of said clamp when the operator depresses a finger piece projecting through an opening in the platen.

30 Another object of my invention is to provide improved card clamping and controlling means in which the releasing and clamping movements of the clamp are in a straight line perpendicular to the axis of the platen.

35 Another object of my invention is to provide improved means for controlling a card clamp which is particularly adaptable to card clamps of considerable length.

Still another object of my invention is to so 40 construct the card clamping and controlling means that they may be supplied in separate units, and one or more units may be readily applied to a platen in accordance with the requirements of the user.

45 To the above and other ends which will hereinafter appear my invention consists in the features of construction, arrangement of parts and combination of devices set forth in the following description and particularly pointed out in the appended claims.

In the accompanying drawings wherein like reference characters indicate corresponding parts in the different views:

50 Fig. 1 is a longitudinal sectional view through a platen equipped with card clamping devices

of my invention, and showing said devices in their clamped position;

Fig. 2 is a front view of the platen, with parts broken away and in section, showing the clamping devices in their released or opened position; 5

Fig. 3 is an enlarged fragmentary, horizontal, sectional view taken along the line 3—3 of Fig. 1 and looking in the direction of the arrows at said line;

Figs. 4 and 5 are enlarged, detail, transverse, 10 sectional views of the platen, together with the feed rolls and paper apron, the sections being taken along the lines 4—4 of Fig. 1 and 5—5 of Fig. 2 respectively, and looking in the direction of the arrows at said lines; 15

Fig. 6 is a front view of a platen equipped with a plurality of independently operable card clamps of my invention;

Fig. 7 is a front view of a platen, with parts broken away and in section, equipped with an- 20 other form of card clamping device embodying my invention.

The mechanism of my present invention, with the above mentioned objects in view, as well as others which will hereinafter appear, may be 25 said to be in the nature of an improvement on the construction disclosed in my Patent No. 1,952,053 dated Mar. 27, 1934.

In the present instance I have shown two forms 30 of my invention, one shown in Figs. 1 to 5 in which the pressure for releasing the card clamp is applied to a card clamp carrier at two points at equal distances from the center thereof, and thus said pressure is distributed substantially equally throughout the length of the clamp; and 35 a second form, shown in Fig. 7 in which the pressure for releasing the clamp is applied at one point directly at the center of the card clamp carrier, and again is distributed substantially equally throughout the length of the clamp. Both 40 of these forms of my invention are shown in the present instance embodied in a platen of a No. 10 Remington noiseless machine although they are also applicable to the platens of other Remington machines, and may in fact be employed 45 in platens of typewriting and line machines generally, wherever found available.

I shall first describe the construction in which pressure for releasing a card clamping member is equally applied to the companion card clamp 50 carrier at two different points at equal distances from the center thereof.

Referring particularly to Fig. 1, it will be seen that the cylindrical platen, which is designated as a whole by the reference numeral 10, in the 55

present instance comprises an inner metal shell or core 11 surrounded by a rubber sheath or covering 12, and the usual platen heads 13 fitted into the core 11 at the ends thereof and secured thereto by means of screws 14. Each of the platen heads is provided with the usual hub portion 15, by means of which the platen 10 may be connected to the usual finger wheels (not shown) and supported for rotative movement on the carriage of a typewriting machine. When the platen is properly mounted on the carriage of a typewriting machine it cooperates with the usual feed rollers 16 (Figs. 4 and 5) which extend through openings 17 in a paper apron 18, such construction being usual in Remington machines.

The platen is apertured, as at 20, throughout the length thereof to receive one or more series of pins 21. The apertures may be substantially conical in shape having the smaller diameter at the inside or core 11 of the platen to provide a supporting fit for the pins which are adapted for movement through said apertures in lines perpendicular to the axis of the platen and without contact with the rubber covering 12. The pins of each separate series are fastened by any suitable means such as the rivets 22, as shown in Figs. 4 and 5, and project from a sheet metal support or carrier 23 of comparatively light stock that is preferably angular in cross section to add to the rigidity of the carrier. Each carrier 23 is provided at the right-hand end thereof (Fig. 1) with an upwardly bent ear 24 which further increases the rigidity of the structure, and at the lefthand end thereof is provided with a downwardly bent ear 25, both of said ears being formed integral with the base portion of the carrier to which the pins 21 are secured. As shown in Fig. 3 the ear 25 is slotted at 26 to receive and guide a releasing member, the purpose of which will hereinafter more clearly appear.

The outer ends of the pins 21 of each series are tapped as indicated at 27 in Fig. 5, to receive headed screws 28 by which a card clamping plate or member 30 is detachably secured to said pins. In practice it may only be necessary to provide a screw 28 for every other pin of a series, as indicated in Fig. 1. It is desirable, however, to employ a comparatively close arrangement of the pins 21 in order that they, together with a stop pin 31 (Figs. 1 and 2) provided at the end of the clamping member, may constitute an effective abutment against which an edge of a card C may bear and be squared as indicated in Figs. 4 and 5, even when a very narrow card is employed. Furthermore, the pins 21 aid in guiding the clamping member 30 in its movement in a direction perpendicular to the axis of the platen and in applying an effective pressure to the clamping plate 30 from the springs 33 as will presently appear.

As shown in Figs. 4 and 5 the card clamping member 30 for each series of pins corresponds in cross section to a segment of the platen, the outer surface of each member 30 when the latter is closed being substantially flush with and forming virtually a continuation of the outer surface of the platen. Therefore, when the card clamp or clamps are not in use as such, the platen may function as usual with an ordinary work sheet. The platen 10 is cut away, as at 32, in order to aid in presenting a substantially smooth and uninterrupted surface when the clamping member 30 occupies its clamping or closed position as shown in Fig. 4. By maintaining the surface of

the platen substantially smooth and uninterrupted there is the further important advantage that the front edge of the paper apron 18 will not engage the clamping member or members 30 during the backward feeding of a card or work sheet or when the platen receives a clockwise movement as the parts are shown in Fig. 5. Of course the platen may also be turned in an opposite direction without the clamping members 30 fouling on the paper apron.

It will be seen that each member 30 is secured to its series of pins 21 along the longitudinal median line of said member so that an equal amount of clamping surface is provided on each side of each set of pins 21 to allow cards C to be clamped on either side of each set of pins. Thus, either a front or back feed of a card may be effected as desired.

Since each card clamp and its releasing means is the same as the other or others, where more than one clamp is employed, the specific description of one will likewise apply to the others.

Surrounding each of the pins 21 is a coiled expansion spring 33 that bears at one end against the carrier 23, and at its opposite end bears against the inner surface of the platen core 11 at an annulus adjacent the smaller inside opening of the conical aperture 20. Such a construction is possible in the present instance since the diameter of each of the apertures 20 at its opening into the platen core is only slightly larger than the diameter of the associated pin 21 to enable, as pointed out above, said pins to move in said apertures in a direction perpendicular to the axis of the platen and be supported and guided during such movement. The construction and arrangement of the parts are such that the effective force of each series of springs 33 is efficiently exerted to normally maintain the companion parts in the Fig. 1 or Fig. 4 position with the clamping bar pressed with a substantially equal force throughout its length against the outer cut away portion 32 of the platen and to firmly hold the engaged edge of a card against the platen and cause the card to be fed with the platen either with a back feed or a front feed. Since the amount of force exerted by the springs need only be great enough to firmly and effectively hold the cards in clamping position, it may be found unnecessary to provide a spring 33 about each of the pins 21, and the required number of springs 33 may be distributed in any suitable manner about the pins 21 as shown, for example, in Fig. 1. However, in distributing the required number of springs to maintain an effective pressure, it is advantageous to have the disposition substantially uniform so that the effective force of said springs will be equally and efficiently distributed along the clamping bar substantially throughout its length. Having a uniform distribution of the springs 33, and having each of the clamping members 30 secured to its series of pins 21 along the longitudinal median line of said member, it will be apparent that the clamping force or pressure of the springs 33 will be equally distributed on either side of each set of pins.

In order to effect a release of each card clamp, I have provided, in the present instance, a separate independently operable finger piece 35 for each unit, and each finger piece in the normal position of the associated parts represented in Fig. 4, has its outer contact face substantially flush with the surface of the platen. Each finger piece moves in an opening 36 provided in the platen and is located outside the field of the associated

card clamp, or any of them, being preferably offset to the left of the associated card clamp, as indicated in Figs. 1 and 2. The relative arrangement of the parts is such that access may be readily had to a finger piece 35, or each of them, when the platen is in the card receiving position. Directly connected with each finger piece 35 is a stem or plunger 37 which is pivoted at its lower end, at 38, to a primary control or releasing lever 40 contained wholly within the platen. In order to effectively maintain the pivotal connection between the key stem and lever, and yet permit a ready disconnection and reconnection between the parts when desired, I prefer to employ a leaf spring 41 riveted at 42 to each stem 37, the free end of said spring overlapping the associated lever 40 and the pivot 38 carried thereby.

Referring particularly to Figs. 3 and 5 it will be seen that each lever 40 is fulcrumed substantially at the center thereof with the aid of a headed pivot pin 43 which pivots in an opening 44 provided in a pivot post or support 45. This pivot post is pivotally and removably mounted by means of an extended pivot pin 46 removably supported in a pivot bearing, support or hanger 47 which is riveted to the inner wall of the platen core 11, as shown in Figs. 1 and 5, thus providing a floating fulcrum for the lever 40 for purposes which will hereinafter appear. At its right-hand end the control lever 40 is connected to a bracket 48 by means of a headed pin 50 riveted to said lever and received in a slot 51 provided in the bracket 48. The bracket 48 is spot welded, or secured by any other suitable means, to the under side of the carrier 23, at a point substantially midway between the center of said carrier and the right-hand end thereof, and thus a releasing force applied from the finger piece 35 to the bracket will be transmitted to the carrier through the bracket and transmitted to the clamp 39 through the pins 21.

It will be apparent that if pressure is applied to the finger piece 35 it will cause the control lever 40 to turn in a counter-clockwise direction about its pivot 43 as the parts are depicted in Fig. 1, to transmit a force to the carrier member 23 as pointed out above, and thus tend to effect a raising or releasing of the clamping member 39. However, in order that the pressure applied in the depression of the finger piece 35 may be distributed substantially equally along the carrier member 23 and likewise along the clamp 39, I have provided a secondary control or releasing lever 52 which is pivotally supported by means of a headed pin 53 on a pivot post 54 like the post 45. The pivot post 54 is also removably and pivotally mounted by means of the extended pin 46 in a support or hanger 55 which is riveted, or secured by any other suitable means, to the inner wall of the core 11 in substantial alignment with the support 47 for the control lever 40. This provides a floating fulcrum for the lever 52. The secondary control lever 52 is connected to a bracket 56 by means of a headed pin 57 riveted to said lever and received in an elongated slot 58 provided in the bracket 56, which bracket 56 is spot welded, or secured by any other suitable means, to the under side of the carrier 23 at a point midway between the center of said carrier and the left-hand end thereof.

Substantially midway between the two fulcrums 43 and 53 for the primary and secondary control levers 40 and 52 respectively, I have connected said levers by means of a headed pin 60 provided in the primary lever 40 and received in

an elongated slot 61 in the secondary lever 52. Thus, it will be seen, when the primary control lever 40 is turned in a counter-clockwise direction (Fig. 1) about its pivot or fulcrum 43, motion will be transmitted to the secondary lever 52 through the pin and slot connection 60, 61; and it is to be understood that the construction of the above described mechanism is such that when the finger piece 35 is depressed, pressure will be distributed substantially equally throughout the length of the carrier 23 and card clamp 39 to effect a releasing of said card clamping member against the tension springs 33, and the parts will change from the closed position of the clamp shown in Fig. 1 to the released position shown in Fig. 2. In distributing the releasing pressure from the control levers, in effect, the primary control lever 40 acts on half of the pins 21 while the secondary control lever 52 simultaneously acts on the remaining pins in the series. From Figs. 2 and 5 it will be observed that the releasing movement of the card clamping member 39 is limited by contact of the upwardly bent flange and the ear 24 of the carrier 23 with the inner surface of the core member 11. Moreover, it will be understood that this contact also limits the downward movement of the finger piece 35 and plunger 37.

It is to be understood that the card clamping member and all the operating parts associated therewith and described above lie in substantially the same diametrical plane, that the floating fulcrums for the primary and secondary control levers are in a line substantially diametrically opposite the line of the card clamp 39, and that the clamping and releasing motion of the card clamping member 39 is a straight line motion and in a direction perpendicular to the axis of the platen. It will be apparent moreover, that with the floating fulcrum construction described above, the associated operating parts will be self-finding and any binding tendency in operation will be relieved. Furthermore, it is to be understood that the primary and secondary control levers, together with their various connections etc. constitute a controlling means intermediate the finger piece and the carrier for aiding in effecting the above mentioned straight line motion.

In assembling the parts of each clamping unit, each carrier 23, with the parts carried thereby is fitted together before introduction into the platen. That is, the pins 21 with the necessary springs 33, and the levers 40 and 52 with their associated pivot posts 45 and 54 respectively, are connected to the carrier 23, and this assembly is inserted into the platen which has either one or both of the platen heads 13 removed therefrom. When this unit has been introduced into the platen, the pins 21 on each carrier are inserted from inside the platen through the apertures 20 and the associated clamping plate 28 is then secured to said pins, as described above, by means of the screws 28. Previous to the insertion of the carrier 23 and its associated parts the supports or hangers 47 and 55 have been riveted to the inner wall of the core 11 in their proper positions diametrically opposite the line of the apertures 20, so that after the pins 21 have been inserted into the apertures 20, or substantially simultaneously therewith, the pivot posts 45 and 54 may be fitted into their respective supports. The extended pivot rod 46 may then be introduced endwise through the openings in each of the supports and its associated pivot post. The finger piece 35 and its associated plunger 37 for each clamping assembly

may then be inserted through the opening 36 and connected at its pivot 38 to the companion primary controlling lever 40. The platen heads 13 may then be fitted into the core 11, and the assembled platen and card clamping device are then ready to be mounted on the carriage of a typewriting machine.

In Fig. 7 I have shown another form of construction embodying my invention in which a single control lever is associated with each finger piece to apply the pressure or force for releasing the clamping member to the center of the carrier and thus distribute the releasing pressure substantially equally throughout the length of the associated clamp. I shall now describe this modified form of my invention.

As in the above described form of my invention, the present construction of the card clamping member or device is only one of a series of such devices that may be mounted within a platen, the number of card clamps used in any particular instance depending in general upon the length of platen employed.

Referring particularly to Fig. 7 it will be observed that the cylindrical platen which is designated as a whole by the reference numeral 65, in the present instance, comprises an inner metal core or shell 66 surrounded by a rubber sheath or covering 67, and the usual platen heads 68 fitted into the core 66 at the ends thereof and secured thereto by any suitable means. The platen heads are provided with the usual hub portions 69, by means of which said platen may be mounted for the usual rotative movement on the carriage of a typewriting machine, and when so mounted cooperates with the usual feed rollers similar to those described above and shown in Figs. 4 and 5.

The clamping devices used in the present instance comprise a clamping member 70, like the member 30, mounted on pins 71 which pass through apertures 72 to the inside of the platen where said pins are mounted on a carrier 73. Each clamping member 70 fits into a cut out portion 74 on the platen surface, and in the normal position is maintained substantially flush with said platen surface by means of a series of springs 75 surrounding the pins 71. At their upper ends the springs 75 bear against the inner surface of the platen core 66 on an annulus adjacent each aperture 72 and at their lower ends bear against the carrier member 73. The carrier member 73 is similar to the carrier member 23 and like said member is angular in cross section and provided at the left-hand end thereof with a downwardly bent ear 76 which is slotted to receive and guide a control member as will hereinafter more clearly appear.

In order to effect a release of each card clamp, I have provided a finger piece 77 mounted upon a stem or plunger 78, and fitting in an opening 77a in the platen surface to lie in normal clamping position, substantially flush with said surface. The stem or plunger 78 is removably pivoted at 79 to a control lever 80, said pivotal connection being releasably maintained by means of a leaf spring 81 riveted to the side of said plunger 78. As thus far described the construction shown in Fig. 7 is similar to that disclosed in the remaining figures and described above.

Each of the control levers 80 is provided with a raised portion 82 on the lower edge thereof which is adapted to bear against the inner surface of the platen shell or core 66 to provide a floating fulcrum for said lever. This raised

portion 82 is substantially midway between the pivot 79 at the left-hand end of the lever 80, and a pivot 83 at the right-hand end of said lever. The pivot 83 is the means by which the control lever 80 is connected to a bracket 84 which is spot welded, or secured by any other suitable means, to the under side of the carrier 73 substantially at the center thereof. The above described construction is such that when the finger piece 77 is depressed, the control lever 80 will be turned in a counter-clockwise direction about the fulcrum 82 to effect a raising of the clamping member 70 against the tension of the springs 75. This releasing motion of the clamping member may be limited by the provision of a pair of stop or limiting pins 85 which may be mounted upon the carrier 73. As shown in Fig. 7 when the carrier member is raised or moved in a releasing direction, the tops of the stop pins 85 will contact the inner surface of the platen shell 66 and thus limit releasing movement. When the operator removes his finger from the finger piece 77, the parts will return to the position shown in Fig. 7 due to the effect of the springs 75. The control lever 80 is resiliently held in its normal Fig. 7 position with the fulcrum portion 82 thereof contacting the shell 66 by means of a spring 86 surrounding a pin 87 which projects downwardly from the under side of the carrier member 73. The spring 86 bears at its upper end against the carrier 73 and at its lower end against the upper edge of the control lever 80 at a point to the left of the pivot 83 so that it will resiliently hold the lever 80 from turning in a clockwise direction about said pivot 83.

It is to be understood that the pins 71 guide the clamping member 70 in its straight line opening and closing movements in a direction perpendicular to the axis of the platen, and when a releasing pressure is applied to the carrier 73 at substantially the center thereof, said pressure will be equally distributed throughout the length of the carrier.

In mounting a series of card clamping devices, 45 as described above, within a platen, the entire actuating mechanism including the carrier 73 and the parts carried thereby are assembled outside the platen and introduced therein as a single unit when either or both of the platen heads 68 have been removed. The pins 71 are then introduced through the apertures 72 from the inside of the platen, the clamping member 70 is secured to said pins, and the finger piece and plunger are inserted and pivoted to the control levers. Each unit is assembled in the same general manner.

From the foregoing description it will be apparent that I have provided improved means whereby a plurality of independently controlled clamps may be employed on a single platen to enable a plurality of cards to be successively clamped in position and fed at one movement, thereby materially increasing the speed at which cards may be written. It will also be apparent that I have provided an improved card clamping means which is particularly adaptable to card clamps of considerable length capable of use with either narrow or wide cards or labels, and with which either a forward or backward feed of the card may be effected with equal facility without reversing the platen end-for-end or in any manner modifying the construction.

It is to be understood that in both of the embodiments of my invention the following are 75

some of the features and advantages of the construction:

(a) The construction and arrangement of parts is such that the pressure of the springs is exerted efficiently on a clamp with substantially equal force throughout the length thereof, thereby allowing small or odd shaped cards to be effectively clamped at any point throughout the length of the clamp and on either side thereof.

(b) When the operator depresses a finger piece projecting through an opening in the platen, the releasing pressure thus applied is equally distributed throughout the length of the clamp, thereby raising said clamp a uniform distance throughout the length thereof to allow all cards held thereunder to be released simultaneously.

(c) The releasing or clamping movement of any particular clamp is a straight line motion in a radial plane of the platen upon which or in which said clamp is mounted thereby permitting the use of close fitting apertures for the supporting and guiding pins and allowing a forward and backward feed clamp to be employed.

(d) By using a floating fulcrum construction in each instance the associated operating parts are self-finding and there is no liability of the parts binding or becoming cramped in operation.

(e) By the arrangement of the parts in the manner described so that they all operate substantially in the same radial plane in or on the platen there is little liability of cramping or undue binding of the parts in their operation.

(f) Due to the fact that the control levers for releasing the clamp extend longitudinally of the platen and within it comparatively long levers may be employed for effectively releasing the clamp to an equal extent throughout the length thereof as above pointed out.

(g) The construction and arrangements of the parts, moreover, are such as to enable them, in the main, to be assembled outside of the platen and be readily introduced therein.

Various changes may be made in the construction and certain features thereof may be employed without others, without departing from my invention as it is defined in the accompanying claims.

What I claim as new and desire to secure by Letters Patent is:

50. 1. The combination of a hollow cylindrical platen having openings therein, a carrier disposed within said platen, a series of pins on said carrier which project through said openings in the platen, a card clamp carried by said pins, springs surrounding said pins and exerting their force against said carrier, a finger piece, and controlling means intermediate said finger piece and carrier for imparting a straight line movement to the latter against the force of said springs to release the card clamp, said last mentioned means comprising interconnected levers controlled by said finger piece and acting on said carrier.

65. 2. The combination of a hollow cylindrical platen having openings therein, a carrier disposed within said platen, a series of pins on said carrier which project through said openings in the platen, a card clamp carried by said pins, springs surrounding said pins and exerting their force against said carrier, a finger piece, and controlling means intermediate said finger piece and carrier for imparting a straight line movement to the latter against the force of said springs to release the card clamp, said last mentioned means comprising a lever controlled by said finger piece and acting on said carrier, and a second

lever controlled by said first lever and acting on said carrier.

3. The combination of a hollow cylindrical platen having openings therein, a card clamp substantially flush with the surface of said platen, supporting and guiding pins attached to said clamp and extending through said openings in said platen, a finger piece, and controlling means intermediate said finger piece and said supporting pins for imparting a straight line motion to said pins to move said clamp, said controlling means comprising interconnected levers controlled by said finger piece and acting on said supporting pins.

4. The combination of a hollow cylindrical platen having openings therein, a card clamp substantially flush with the surface of said platen, supporting and guiding pins attached to said clamp and extending through said openings in said platen, a finger piece, and controlling means intermediate said finger piece and said supporting pins for imparting a straight line motion to said pins to move said clamp, said controlling means comprising a lever controlled by said finger piece and acting more directly on half of said supporting pins, and a second lever controlled by said first lever and acting more directly on the remainder of said supporting pins.

5. The combination of a hollow cylindrical platen having openings therein, a card clamp substantially flush with the surface of said platen, supporting and guiding pins attached to said clamp and extending through openings in said platen, a finger piece, and controlling means intermediate said finger piece and said supporting pins for imparting a straight line motion to said pins to move said clamp, said controlling means comprising a lever controlled by said finger piece and acting more directly on half of said supporting pins, and a second lever controlled by said first lever and acting more directly on the remainder of said supporting pins, both of said levers being fulcrumed on the inside of said hollow platen in a line diametrically opposite the line of said supporting pins and card clamp.

6. The combination of a hollow cylindrical platen having openings therein, a card clamp substantially flush with the surface of said platen, supporting and guiding pins attached to said clamp and extending through said openings in said platen, resilient means holding said clamp in clamping position, a finger piece, and controlling means intermediate said finger piece and said supporting pins for imparting a straight line motion to said pins to release said clamp, said controlling means comprising interconnected levers controlled by said finger piece and acting on said supporting pins.

7. The combination of a hollow cylindrical platen having openings therein, a card clamp substantially flush with the surface of said platen, supporting and guiding pins attached to said clamp and extending through openings in said platen, resilient means holding said clamp in clamping position, a finger piece and controlling means intermediate said finger piece and said supporting pins for imparting a straight line motion to said pins to release said clamp, said controlling means comprising interconnected levers controlled by said finger piece and fulcrumed at 70 points within said platen diametrically opposite the line of said supporting pins.

8. The combination of a hollow cylindrical platen having openings therein; a plurality of independently releasable card clamps carried by

and arranged in alignment along the platen; springs contained within the platen for pressing said clamps separately to clamping position; a separate carrier for each clamp disposed within the platen; a series of pins on each carrier that project through said openings in the platen, one of the card clamps being fixed to each series of said pins; a separate and independently operable finger piece for each clamp; controlling means intermediate each finger piece and carrier for imparting a straight line movement to the latter against the force of said springs, said controlling means for each clamp comprising interconnected levers controlled by the associated finger piece and acting on the companion carrier, each of said levers being fulcrumed on a pivot post which is pivoted in a hanger, and the hangers for all of said pivot posts being secured to the inner wall of said platen in a line diametrically opposite the line of the card clamps, and a single pivot rod passing through all of said pivot posts and hangers and extending substantially throughout the length of the platen.

9. The combination of a hollow cylindrical platen having openings therein, a carrier disposed within said platen, a series of pins on said carrier which project through said openings in the platen, a card clamp carried by said pins, springs surrounding said pins and exerting their force against said carrier, a finger piece that projects through an opening in the platen, and controlling means intermediate said finger piece and said carrier for imparting a straight line movement to said carrier to release said card clamp, said controlling means comprising a single lever pivotally connected to said carrier at the center thereof and fulcrumed on the inner surface of said platen at a point diametrically opposite the line of said clamp.

10. The combination of a hollow cylindrical platen having openings therein, a carrier disposed within said platen, a series of pins on said carrier which project through said openings in the platen, a card clamp carried by said pins, springs surrounding said pins and exerting their force against said carrier, a finger piece that projects through an opening in the platen, and controlling means intermediate said finger piece and said carrier for imparting a straight line movement to said carrier to release said card clamp, said controlling means comprising a single lever pivotally connected to said carrier at the center thereof and fulcrumed on the inner surface of said platen at a point diametrically opposite the line of said clamp, and means for resiliently maintaining said lever in normal position.

11. The combination of a platen, a card clamp extending longitudinally thereof and mounted for rectilinear movement into and out of contact with the platen, springs which exert their force on said card clamp in the general direction of its rectilinear movement, a finger piece for releasing said clamp, and releasing means controlled by said finger piece and comprising a lever which extends longitudinally of and within the platen and is fulcrumed thereon, said lever moving substantially in the plane of movement of said clamp.

12. The combination of a rotative platen having openings therein, a series of pins extending radially of the platen through said openings, a card clamp extending longitudinally of the platen and connected along the median line thereof to said pins so that the card clamp extends in sub-

stantially equal amounts on opposite sides of said series of pins and cooperates with a card introduced beneath the clamp from either direction and effects either a forward or backward feed of the card, said clamp being mounted for rectilinear movement radially of the platen into and out of clamping position, springs exerting their force on said clamp in the general direction of its movement, and means for releasing said clamp against the force of said springs comprising a lever extending longitudinally within said platen and fulcrumed thereon, said lever moving substantially in the same radial plane as said clamp, and a finger piece for controlling said lever.

13. The combination of a rotative platen having openings therein, a series of pins extending radially of the platen through said openings, a card clamp extending longitudinally of the platen and connected along the median line thereof to said pins so that the card clamp extends in substantially equal amounts on opposite sides of said series of pins and cooperates with a card introduced beneath the clamp from either direction and effects either a forward or backward feed of the card, said clamp being mounted for rectilinear movement radially of the platen into and out of clamping position, a carrier contained within and extending longitudinally of the platen and to which said pins are affixed, springs surrounding said pins and bearing against said carrier and against the platen, and means for releasing said clamp against the force of said springs comprising a lever extending longitudinally within said platen and fulcrumed thereon, said lever moving substantially in the same radial plane as said clamp, and a finger piece for controlling said lever.

14. The combination of a rotative platen having openings therein, a series of pins extending radially of the platen through said openings, a card clamp extending longitudinally of the platen and connected along the median line thereof to said pins so that the card clamp extends in substantially equal amounts on opposite sides of said series of pins and cooperates with a card introduced beneath the clamp from either direction and effects either a forward or backward feed of the card, said clamp being mounted for rectilinear movement radially of the platen into and out of clamping position, a carrier contained within and extending longitudinally of the platen and to which said pins are affixed, springs surrounding said pins and bearing against said carrier and against the platen, and means for releasing said clamp against the force of said springs comprising a lever contained within and extending longitudinally of the platen and connected to said carrier near one end portion of the latter, a finger piece for controlling said lever, and a second lever controlled in its movement by said first mentioned lever and connected with said carrier near the other end portion of the latter.

15. The combination of a rotative platen having openings therein, a series of pins extending radially of the platen through said openings, a card clamp extending longitudinally of the platen and connected along the median line thereof to said pins so that the card clamp extends in substantially equal amounts on opposite sides of said series of pins and cooperates with a card introduced beneath the clamp from either direction and effects either a forward or backward feed of the card, said clamp being mounted for rectilinear movement radially of the platen into and

out of clamping position, a carrier contained within and extending longitudinally of the platen and to which said pins are affixed, springs surrounding said pins and bearing against said carrier and against the platen, and means for releasing said clamp against the force of said springs comprising a lever contained within and extending longitudinally of the platen and connected to said carrier near one end portion of the latter, a

finger piece for controlling said lever, and a second lever controlled in its movement by said first mentioned lever and connected with said carrier near the other end portion of the latter, the planes of movement of said levers being substantially in the plane of movement of said carrier and clamp. 5
